UNITED STATES PATENT OFFICE.

JOHN KRALUND AND CLARENCE H. DUCKWORTH, OF BROOKLYN, NEW YORK, AND MARCUS STERN, OF TOLEDO, OHIO, ASSIGNORS TO DOEHLER DIE CASTING COMPANY, OF BROOKLYN, NEW YORK, A CORPORATION OF NEW YORK.

METHOD OF AND APPARATUS FOR MAKING CASTINGS.

Application filed June 18, 1920. Serial No. 389,821.

To all whom it may concern:

Be it known that we, JOHN KRALUND, CLARENCE H. DUCKWORTH, and MARCUS STERN, all citizens of the United States, the 5 first two above named residing in the borough of Brooklyn, county of Kings, city and State of New York, and the third above named residing at Toledo, in the county of Lucas and State of Ohio, have invented 10 certain new and useful Improvements in Methods of and Apparatus for Making Castings, of which the following is a specification.

Our invention relates to a method of and 15 apparatus for making castings, particularly die castings. In the use of a two part or other multiple part die or mold in which the gate opening extends through one of the parts of the mold and the mold cavity is 20 located wholly or in part in another section of the mold, difficulty sometimes arises when the mold sections are separated because of the sticking of the gate metal to the section of the mold through which the gate opening 25 extends. Such adhesion of the gate metal is liable to injure the casting by exerting a pull on the same before it has sufficiently hardened, whereby portions of its surface may be broken off, etc.

30 We overcome this difficulty and also produce other beneficial effects by locating within the gate opening a member about which the molten metal will flow when the mold is poured and about which the metal will 35 shrink when the metal chills as the mold sections are separated. This member preferably takes the form of a tapered pin which extends into the gate opening, when the mold is closed, from the adjoining mold 40 section. This pin is properly shaped to direct the molten metal smoothly toward and into the mold cavity or cavities. Its provision likewise lessens the amount of metal in the gate which is, of course, an advantage.

45 Likewise as stated above, it provides a core about which the metal will shrink when it cools so as to prevent adhesion of the outer periphery of the gate with the gate opening through which it extends. Our invention 50 consists in the process of pouring the casting about and around such a member, as the metal flows to the mold cavity or cavities and in holding this member in such position, when the metal is chilled and the

mold parts are separated, that the gate 55 metal will shrink about the member and permit the ready separation of the mold member containing the gate opening from the adjoining mold member. Our invention also 60 consists in suitable apparatus by which the process referred to may be practiced.

In order that a clearer understanding of our invention may be had, attention is hereby directed to the accompanying drawing forming part of this application and illustrating one manner in which our improved process may be practiced, together with improved apparatus for practicing the same. In the drawings, Fig. 1 represents a vertical section through apparatus comprising 70 our invention; Fig. 2 is a partial sectional view of apparatus similar to that shown in Fig. 1, showing a modified form of gate pin; and Fig. 3 is a similar view showing a further modified form of gate pin. 75

Referring to the drawings, we have illustrated a die or mold having sections 1 and 2, the gate opening 3 extending through the mold section 1, and mold cavities 4, 4 being formed in mold section 2. It is obvious 80 that the mold cavities might be formed partly in section 2 and partly in section 1, and also that a mold or die having more than two sections might be employed.

In the apparatus illustrated the mold or 85 die section 1 is secured to a frame 5 through which extends an opening in alinement with the gate opening 3 of mold section 1, this opening through frame member 5 being provided with a sleeve 6. Mold section 2 90 is secured to a frame 7 which is adapted to be moved horizontally in opening and closing the mold.

Molten metal is forced or poured through the sleeve 6 and gate opening 3, when the 95 mold is closed, by any suitable means. In the apparatus shown in the drawings, the metal is forced through the alined gate openings under pressure from the nozzle 8 of a movable carrier 9 which is adapted to dip into the metal in a melting pot 10, after which nozzle 8 is positioned within the mouth of the sleeve and the molten metal forced therethrough by air pressure, in accordance for example with Patent 1,299,738 100 of John Kralund, dated April 8, 1919.

The pin or post 11 is positioned, within or secured to mold section 2, this pin having

a tapered extension 12 which projects longitudinally into the gate opening 3 when the mold is closed. This tapered pin 12 is suitably shaped to divide the stream of molten metal which forms the gate 13 so that the same will smoothly flow through the runs 14, 14 into the mold cavities 4, 4. The metal forming the gate entirely surrounds the tapered pin 12 and shrinks about the same when the mold sections are separated so as to prevent adhesion of the peripheral surface of gate 13 with the wall of the gate opening 3. Mold section 2 being separated from mold section 1 by moving frame 7 and mold section 2 to the left, referring to Fig. 1 of the drawings, the gate will adhere to the tapered pin 12 which moves to the left with mold section 2. It will, therefore, come away from mold section 1 easily and without sticking thereto. The surface of tapered pin 12 may be roughened, if desired, to increase the adhesion of the gate metal to the same when the metal shrinks thereto.

As stated above, the positioning of pin 12 within the gate opening decreases the amount of metal forming the gate which is, of course, an advantage, since the gate metal must subsequently be melted up for future use.

30 In the construction shown in Fig. 1, pin 11 is secured to a member 15 which is carried by a reciprocable member 16. This latter is provided with a rack 17 with which a pinion 18 engages. Pin or post 11 extends through a suitable opening in the mold member 2 within which it closely fits. Member 15 is adapted to move horizontally in an opening 19 in the frame member 7. When the pin 11 has been properly adjusted 40 within the mold member 2, the pinion 18 is held stationary so that pin 11 will only move with mold member 2. Pin 11 is, therefore, in effect secured to mold member 2, the provision of member 15 permitting substitution of one gate pin or post 11 for another when a change becomes necessary.

In the form of apparatus illustrated in Fig. 1, cores 20, 20, about which the castings in cavities 4 are formed, are illustrated as 50 secured to member 15. An additional member 21 is shown as mounted for movement within the recess 19, this member carrying the ejecting pins 22 which extend through openings in member 15 and aligned openings 55 in mold member 2. Member 21 may be carried by and secured to a rack bar 23 which is adapted to be reciprocated by pinion 24. When the mold has been opened and the castings are to be ejected, member 21 and 60 pins 22 are moved to the right, referring to Fig. 1, to eject the finished castings.

Various shapes of gate pin may be used under different conditions. The pin illustrated in Fig. 1 has been found useful when 65 aluminum was being cast. The pin 12' il-

lustrated in Fig. 2 has been found advantageous when casting white metal. This pin is illustrated as extending from the mold section 2' into the gate opening 3' in the mold section 1'.

The pin 12' shown in Fig. 3 is particularly advantageous for properly directing the molten metal to a mold cavity 4' in mold section 2', the mold cavity in this case being located on one side only of the gate pin. 75 As is illustrated, the pin is provided on the side adjacent the mold cavity 4' with a curved surface 25 adapted to smoothly direct the molten metal into the run 26 leading to the mold cavity. This is intended 80 for use in casting aluminum.

It is thought that the method of practicing our improved process, and the manner of using the apparatus described will be evident from the above. It should be understood that our invention is not limited to the details of construction described, but is as broad as is indicated by the accompanying claims.

What we claim is:—

1. In a device of the character described, the combination with a mold cavity, of means comprising a gate-opening for directing molten metal into said mold cavity, and means for preventing, cooling, gate metal 85 from adhering to the walls of said opening.

2. In a device of the character described, the combination with a mold cavity, of means comprising a gate-opening separate from the mold cavity for directing molten metal into said mold cavity, and means for preventing, cooling, gate metal from adhering to the walls of the gate opening.

3. In a device of the character described, the combination with a mold cavity, of means comprising a gate-opening for directing molten metal into said mold cavity, and means disposed in said gate-opening for shrinking cooling metal remaining in said opening away from the walls thereof.

4. In a device of the character described, the combination with a multiple-part mold providing a mold cavity, and a gate-opening in one of said mold parts, of a pin adapted to extend longitudinally and centrally into said gate-opening and providing a core for metal cooling in said opening to shrink upon, means for adjusting said pin in said opening, and means for moving said pin and one of said mold parts simultaneously away from said gate-opening.

5. In casting apparatus, a mold having two separable sections defining a mold cavity and a gate opening in one of said sections, means, comprising a pin positioned in said gate opening when said sections are together, whereby gate metal cooling in said opening is caused to shrink away from the walls of said opening, means for removing as a unit the other section and said pin, together with 130

- a casting formed in said cavity and the gate metal, from said first section, and means for separating the casting and gate metal from said second section and said pin.
5. 6. In casting apparatus, the combination of a mold having two separable sections defining a mold cavity and a gate opening in one of said sections, and a metallic pin mounted on the other section and adapted 10 when said sections are together to extend centrally into said opening and to provide a core for metal remaining in said opening to shrink upon when cooling, so as to prevent the metal in said opening from so adhering to the walls of said opening as to become broken from a casting in said cavity when the sections are separated, said pin having a roughened surface to effect a more positive adhesion of cooling gate metal 15 thereto.
7. A process of making castings, comprising, directing molten metal to fill a mold cavity through a gate opening and shrinking the gate metal away from the walls of 20 said opening.
8. A process of making castings, comprising, directing molten metal to fill a mold cavity through a gate opening having a centrally disposed metallic core, and shrinking 25 the gate metal upon said core and away from the walls of said opening.
9. A process of making castings, comprising, directing molten metal to fill a mold cavity through a gate opening having a metallic pin longitudinally and centrally 30 disposed in said opening, shrinking the gate metal upon said pin and away from the walls of said opening, and causing the gate metal adjacent said pin to positively adhere 35 thereto upon cooling.
10. A process of making castings, comprising, flowing molten metal to fill a cavity, formed by two relatively movable sections of a mold, through a gate opening in one of 40 said sections and past a metallic pin mounted on the other section and projecting centrally into said gate opening, permitting the molten metal remaining in said opening when 45 the cavity has become full to cool and to shrink about said pin and to withdraw from the walls of said opening, removing as a unit the second-mentioned mold section, together with the casting, pin and gate metal, from the first-mentioned mold section, and thereafter removing the casting and gate metal from the second mold section.
11. In a device of the character described, the combination with two separable mold sections, providing a mold cavity, and a gate-opening in one of said sections, of a perforation in the other mold section and registering with said gate-opening, a pin 50 movably mounted in said perforation and having a portion adapted to extend centrally into said gate-opening and to provide a core for cooling metal in said opening to shrink upon, means for adjusting said pin in said opening when said mold sections are together, and means for moving said pin and said perforated mold section simultaneously away from the other mold section.
12. In a device of the character described, in combination, a frame having an opening, members providing a mold cavity and a passageway, extending from said frame 55 opening to said mold cavity, for leading molten metal from said opening into said mold cavity, and means, comprising a pin centrally disposed in said passageway intermediate said frame opening and said mold cavity, for preventing metal cooling in said passageway from adhering to the walls thereof.
